UNITED STATES PATENT OFFICE.

LEONARD E. SEELEY, OF WELLINGTON, OHIO, ASSIGNOR OF ONE-HALF TO THOMAS F. CALLEY, OF WELLINGTON, OHIO.

ELECTROLYTIC ALTERNATING-CURRENT CHEMICAL RECTIFIER.

1,339,907.

Specification of Letters Patent.

Patented May 11, 1920.

Application filed June 23, 1919. Serial No. 306,023.

To all whom it may concern:

Be it known that I, LEONARD E. SEELEY, a citizen of the United States, residing at Wellington, in the county of Lorain and 5 State of Ohio, have invented a new and useful Electrolytic Alternating-Current Chemical Rectifier, of which the following is a specification.

This invention relates to improvements in 10 electrolytic alternating-current chemical rectifiers, and pertains more especially to an improved portable rectifier for a low voltage alternating current, such, for instance, as that provided by the ignition magneto 15 netos of Ford automobiles, whereby to transform an alternating current into a periodic direct current used for charging storage batteries and other like purposes.

One object of this invention is to prevent 20 the electrolytic solution from spilling over or escaping out of the cell and hence to render my improved rectifier more especially well adapted for use on an automobile.

Another object is to facilitate the assembly 25 of the component parts of my improved rectifier and to render the device simple and durable in construction and reliable in its operation.

With these objects in view, and to attain 30 any other object hereinafter appearing, this invention consists in certain features of construction, and combinations and relative arrangements of parts, hereinafter described in this specification, pointed out in the 35 claims, and illustrated in the accompanying drawings.

In said drawings Figures 1 and 2 are sectional views of a portable rectifier embodying my invention, Fig. 1 being a vertical 40 section taken along the line 1—1, Fig. 2, looking in the direction indicated by the arrow, and Fig. 2, being a vertical section taken along the line 2—2, Fig. 1, looking outwardly. Fig. 3 is a vertical section taken 45 along the line 3—3, Fig. 1 looking outwardly. Fig. 4 is a horizontal section taken along the line 4—4, Fig. 1, looking downwardly.

The cell of my improved rectifier comprises 50 a receptacle 6 constructed of insulating material, such, for instance, as glass or

porcelain and externally covered at the sides and bottom by a protective casing which is preferably made of wood. The receptacle 6 has an interior chamber 8 for receiving the 55 electrolyte which consists of an electrolytic solution, such, for instance, as phosphate of soda, carbonate of soda and phosphate of ammonium, and 9 indicates the level of the electrolytic solution to be supplied to said 60 chamber. The chamber 8 extends from the bottom of the receptacle 6 upwardly to a substantially horizontal diaphragm 10 arranged within and loosely fitting internally of the upper end portion of said receptacle 65 and spaced downwardly from the upper extremity of said receptacle, and said diaphragm is composed of insulating material, such, for instance, as glass or porcelain. Said diaphragm forms the top wall of the 70 chamber 8 and is supported as will herein-after appear. The level 9 of the electrolytic solution is below the diaphragm 10 so as to form, between said diaphragm and said level, a space for receiving gas evolved by 75 electrolytic action, and said space has an outlet formed by a substantially vertical tube 12 which is composed of insulating material, such, for instance, as glass or porcelain, and rigidly secured to the dia- 80 phragm in any approved manner. The tube 12 is approximately centrally of the diaphragm 10 and extends from said dia- phragm upwardly to and above the upper extremity and externally of the receptacle 85 6 and has its upper end portion externally screw-threaded and provided with a closure consisting of a correspondingly internally screw-threaded cap 13 screwed onto the said portion of said tube. The cap 13 90 (see Fig. 1) is provided centrally with an orifice 14 forming a vent for the escape of gas ascending into said tube from the space between the diaphragm and the level 9 of the electrolytic solution. The tube 12 also 95 forms the inlet of the chamber 8 in supplying said chamber with the electrolytic solution.

Seated on the bottom of the chamber 8 (see Figs. 1 and 2) are two laterally spaced 100 racks 16 of insulating material, such, for instance, as glass or porcelain. Each rack

16 has its upper portion provided with three substantially parallel recesses 17 spaced endwise of the rack, and each of said recesses extends laterally through the 5 rack. Upon the bottom of the central recess in each rack 16 rests a substantially vertical plate 20 composed preferably of aluminum and forming one electrode of the rectifier, and upon the bottoms of the outer 10 recesses in said rack rest two substantially vertical plates 21 preferably composed of iron and forming the other electrode of the rectifier as will hereinafter more clearly appear. It will be observed that the aluminum plate 20 is seated in the racks centrally 15 between the ends of the racks, and that the two iron plates 21 are seated in the racks between the plate 20 and opposite ends respectively of the racks. Obviously therefore 20 the plates 20 and 21 are substantially parallel and spaced laterally and preferably have their body-portions terminating at their upper ends below but in proximity to the level 9 of the electrolytic solution.

25 The aluminum plate 20 is provided at its upper end and at one side of the tubular member 12 with an arm 22 arranged adjacent one side edge of said plate and extending upwardly to the diaphragm 10 and having a laterally projecting portion 23 shown extending over one of the plates 21 and arranged next below and forming a seat or support for the diaphragm. The seat-forming member 23 of the arm 22 (see Fig. 3) is 30 provided with a bracket comprising an upright member 24 which is shown integral with said seat-forming member and extends loosely through a slot 25 formed in the adjacent end of the diaphragm 10 and substantially parallel with the plate 20. The member 24 extends preferably to a point centrally between the diaphragm 10 and the upper extremity of the receptacle 6 where it has a laterally projecting portion 26 forming 35 a seat for a binding post 27 to which the conducting wire 28 is attached. Said binding post is secured to the seat-forming portion 26 of the member 24 in any approved manner. It will be observed that the slot 25 extends to an edge of the diaphragm 10 near one end of said edge, and I would here remark that each iron plate 21 is provided, at its upper end and adjacent the opposite edge of the diaphragm, with an arm 32 extending a 40 upwardly to the diaphragm and having a laterally projecting portion 33 arranged next below and forming a seat or support for the diaphragm. The seat-forming members 33 of the two plates 21 (see Figs. 2 and 4) extend toward and into contact with each other and over but are spaced from the central plate 20, and are provided (see Figs. 2 and 4) with upwardly projecting members 34 which extend loosely through a slot 35 formed in the diaphragm 10. The slot 35 extends to the last-mentioned or adjacent edge of said diaphragm and is arranged centrally between the ends of said edge and substantially parallel with the plates 21. It will be observed that the extension of the 50 slots 25 and 35 to opposite edges respectively of said diaphragm permits the assembly of the diaphragm and the plates 20 and 21 preparatory to their introduction into the receptacle 6. The members 34 are side 55 by side and terminate in superimposed and contiguous laterally projecting members 36 the upper of which forms a seat for a binding post 37 projecting above the receptacle 6 and to which the conducting wire 38 is attached. The binding post 37 is secured to the portions 36 of the members 34 in any approved manner.

The upper end of the receptacle 6 is hermetically sealed at the outer side of the diaphragm 10 by a body of insulating material 40, such, for instance, as paraffin applied in a melted condition after the binding posts are attached to the portions 26 and 36 of the members 24 and 34. 90

By the construction hereinbefore described it will be observed that the insulating diaphragm 10 rests on and is inexpensively but efficiently supported from the seat-forming members 23 and 33 of the electrode-forming plates, and that only cutting away of the body of sealing material 40 from the receptacle 6 is required to render the binding posts, diaphragm and electrode-forming plates free to be removed from said 95 receptacle. 100

What I claim is—

1. In an alternating-current chemical rectifier, a receptacle having an electrolyte-receiving chamber, a substantially horizontal insulating diaphragm arranged internally of the upper end portion of and loosely fitting said receptacle and forming the top wall of said chamber, and an electrode which comprises a plate arranged and supported in said chamber and having a seat for said diaphragm and provided with a member extending through and above the diaphragm for electrically connecting the plate to a conducting wire externally of said chamber, the receptacle being hermetically sealed at the outer side of the diaphragm. 110
2. In an alternating-current chemical rectifier, a receptacle having an electrolyte-receiving chamber, a substantially horizontal insulating diaphragm internally of the upper end portion of said receptacle and forming the top wall of said chamber, and an electrode comprising a plate which affords support to said diaphragm and is provided with a member extending through and above the diaphragm for electrically connecting the plate to a conducting wire exter- 120
- 125

- nally of said chamber, the diaphragm having a slot arranged to accommodate the extension of said member of said plate through the diaphragm, and said slot extending to an 5 edge of the diaphragm.
3. In an alternating-current chemical rectifier, a receptacle having an electrolyte-receiving chamber, a substantially horizontal insulating diaphragm internally of the upper 10 end portion of said receptacle and forming the top wall of said chamber, and an electrode comprising a plate which is arranged in said chamber and provided with a laterally projecting member arranged next below and 15 and forming a seat for the diaphragm, said seat-forming member terminating in an upright member which is integral with said seat-forming member and extends through and above the diaphragm for electrically 20 connecting said plate with a conducting wire externally of said chamber.
4. In an alternating-current chemical rectifier, a receptacle having an electrolyte-receiving chamber, a substantially horizontal insulating diaphragm arranged internally 25 of the upper end portion of said receptacle and forming the top of said chamber, and an electrode comprising a plate which is arranged and supported in said chamber and 30 has its body portion spaced from said diaphragm and provided adjacent a side edge of the plate with an arm extending to the diaphragm and having a laterally projecting portion which is arranged next below and 35 forms a seat for the diaphragm, said seat-forming portion terminating in a member which extends through and above the diaphragm and is adapted to be employed in electrically connecting said plate with a con- 40 ducting wire externally of said chamber, the diaphragm having a slot arranged to accommodate the extension of said member of said seat-forming portion through the dia- 45 phragm, and said slot being substantially parallel with said plate and extending to an edge of the plate.
5. In an alternating-current chemical rectifier, a receptacle having an electrolyte-receiving chamber, a substantially horizontal insulating diaphragm arranged internally 50 of the upper end portion of said chamber, and an electrode comprising two laterally spaced substantially parallel and substantially vertical plates arranged and sup- 55 ported in said chamber and having seats for the diaphragm, the diaphragm being provided with a slot, each of the aforesaid plates being provided with a member engag- 60 ing and extending through said slot and above the diaphragm, and the slot-engaging members of said plates being adapted to be connected above the diaphragm to a conducting wire.
6. In an alternating-current chemical rec-
- 65 tifier, a receptacle having an electrolyte-receiving chamber, a substantially horizontal insulating diaphragm arranged internally of the upper end portion of said chamber, and an electrode comprising two laterally spaced substantially parallel and substantially vertical plates arranged and supported in said chamber, the diaphragm being provided over the space between said plates with a slot, each plate having a laterally projecting member arranged next below and 70 forming a seat for the diaphragm and extending to said slot and provided at said slot with an upwardly projecting member 75 engaging the slot, the slot-engaging members of said plates extending through and 80 above said slot and adapted to be connected to a conducting wire externally of the aforesaid chamber.
7. In an alternating-current chemical rectifier, a receptacle having an electrolyte-receiving chamber, a substantially horizontal insulating diaphragm arranged internally of the upper end portion of and loosely fitting 85 said receptacle and forming the top wall of said chamber and spaced downwardly from the upper extremity of the receptacle and 90 provided with two spaced slots, two spaced electrodes seated in said chamber and having seats for the diaphragm, a body of insulating sealing material at the outer side of 95 said diaphragm, and two binding posts ar- 100 ranged adjacent the different slots respectively in the diaphragm and extending upwardly from within said body of sealing material and adapted to be connected the one to one of two conducting wires and the other to the other of said wires, one of the electrodes being provided with a member which extends upwardly through one of the aforesaid slots and is employed in sup- 105 porting one of said binding posts, and the other electrode being provided with a member which extends upwardly through the other of said slots and is employed in sup- 110 porting the other of said posts.
8. In an alternating-current chemical rectifier, a receptacle having an electrolyte-receiving chamber, a substantially horizontal insulating diaphragm arranged internally 115 of the upper end portion of said receptacle and forming the top wall of said chamber and spaced downwardly from the upper extremity of said receptacle and provided with two slots extending inwardly from opposite edges respectively of the diaphragm, an elec- 120 trode-forming plate seated in said chamber, two electrode-forming plates seated in said chamber at opposite sides respectively of and spaced from the first-mentioned plate, and a body of insulating material sealing the 125 receptacle at the outer side of the dia- phragm, the aforesaid plates having seats for the diaphragm, the first-mentioned plate
